CONTAINER AND CLOSURE THEREFOR

Eino E. Lakso, Fitchburg, Mass., assignor to Vogt Processes, Incorporated, Louisville, Ky., a corporation of Delaware

Application January 9, 1935, Serial No. 992

2 Claims. (Cl. 229—5.5)

My present invention relates to the packaging of plastic material such as ice cream or the like and involves a cylindrical container of paper, cardboard or other fibrous material having a removable flanged cap which may be conveniently manually telescoped over the end of a container and which imposes sufficient frictional resistance to withdrawal, to insure its retention and proper positioning during shipment and storage.

10 A feature of the invention is the provision of a container cap or closure embodying a container-embracing flange including a portion adapted to be placed under circumferential tension as an incident of applying the cap. The flange consists of an annulus of fibrous material affording a circular inwardly extending radially yielding rib so designed that as the cap is applied to the container, the container mouth cams into the rib, expanding it and placing it under tension so that it offers a substantial frictional resistance to removal of the cap.

Another feature of the invention is the provision of a container closure of the general character described above which is of extremely simple, practical, rugged, durable and efficient construction capable of being inexpensively manufactured and consisting merely of a circular closure portion and an annular container-engaging flange-forming member interlocked with the circular closure portion and having a portion bent inwardly to define the rib. The upper edge of the flange forming member is bent inwardly and downwardly to define a bead and the disk-like closure member is locked between the bead and rib of the flange-forming piece.

My improved cap forms a part of my improved package. The relatively light cylindrical shell may be completely filled with ice cream or other plastic material and is thereby reinforced by the cream to such an extent that flexure of the yielding rib of the closure with consequent substantial frictional grip occurs when the cap is forced home. This is in contradistinction to the application of the cap over the mouth of a light unfilled shell where the shell being more flexible than the closure would do most of the yielding itself and but light frictional contact would be had.

Furthermore the disk of my improved closure is of a diameter greater than the mouth of the cylindrical shell to be capped and lies flatly against said mouth contacting its entire periphery when the cap is applied. With the container brim full of plastic or frozen material directly contacting the disk of the closure, a substantial

vacuum effect is created to oppose removal of the cap, this force supplementing the frictional drag of the rib against the outer surface of the shell.

The invention may be more fully understood from the following description in connection with the accompanying drawing wherein:

Fig. 1 is a perspective view of a cylindrical container with my improved closure in applied position,

Fig. 2 is an enlarged broken transverse sectional view through the closure removed from the container and showing the former just before it is forced over the end of the container, and

Fig. 3 is a view similar to Fig. 2 with the closure fully telescoped over the mouth of the cream filled container.

I have illustrated a conventional type of fibrous container 10 consisting of a side wall cylindrical throughout its length and having a bottom 11 secured thereto in any conventional or convenient manner and preferably in such fashion that it is liquid tight. The container may be of light stiff cardboard or other material suitable for the purpose and adapted to encase a partially or fully frozen mass of ice cream or the like which preferably fills the container to the brim.

The closure member indicated generally at 12 includes a flat circular disk 13 preferably of cardboard or other fibrous material having a downwardly bent peripheral rim portion 14, the flat center of the disk being of greater diameter than the mouth of the shell 10. Cooperating with the disk-like closure member 13 to complete the cap is a flange-forming member indicated generally at 15. This flange-forming member is of annular shape, the cylindrical skirt portion 17 thereof being of substantially greater diameter than shell 10. The upper edge of member 15 is rolled inwardly and downwardly as indicated at 16 to form a bead which prevents upward movement of the disk 13.

The main skirt portion 17 of the flange-forming member 15 snugly fits the down-turned rim 14 of disk 13 and extends to an appreciable distance below the rim. Just below the rim 14 however and approximately midway of the skirt portion, the latter is pressed, formed or laterally bent inwardly to define an annular rib 18 which is here illustrated as of generally semi-circular, cross-section presenting a rounded underside adapted to engage the mouth of the container 10 as the cap is applied, and cam over the container. The smallest diameter of the rib is less than the external diameter of the container so that as the

cap is forced home, the rib is expanded and compressed or flattened as indicated in Fig. 3. The diameter of the flat portion of the disk 13 is sufficiently great so that there is no danger of snagging the container mouth on the lower edge of the disk rim 14, substantial clearance being provided between the members 10 and 14 as indicated in Fig. 3. Furthermore the inwardly present rib 18 with its tapering or rounded lower cam surface automatically centers the flange 13 with respect to the container as the cap is thrust home and obviates any danger of the container mouth engaging the disk rim 14.

The upper part of rib 18 contacts or approximately contacts the flange 14 of disk 13 and thus coacts with bead 16 to lock the disk in place. Since the skirt 17 of the flange-forming member 15 is of substantially greater diameter than the container 10, no careful manual manipulation for "fitting" the closure to the shell is required but the cap drops over the shell and the latter is automatically centered with respect to the inclined or tapered under side of rib 18.

The bending or forming of bead 16 and rib 18 appreciably stiffens the flange-forming element 15 so that it has no tendency to lose its circular shape even though made of relatively light material. The ice cream which fills the container 10 reinforces this shell and sustains its shape and permits the shell to positively expand or compress the rib 18 as the closure is pressed home. No air space is present between the flat disk 13 (which makes complete peripheral contact with the container mouth) and the contents of the container. Thus as pull is exerted to remove the cap there is a tendency to create a vacuum between this disk and the ice cream which affords further resistance to removal of the closure.

The casual handling of the caps or closures prior to their application to the container will not result in dis-assembly of the disks with respect to the flange forming elements. The container is of regular cylindrical form and the only member which is distorted as an incident of the application of the cap is the annular compressible or yieldable rib of the cap itself.

In the drawing the thickness of the material and the extent to which the rib is flexed or expanded or flattened as the cap is applied has been greatly exaggerated in order to more clearly visually depict the action which occurs.

Having thus described my invention, what I claim as new and desired to secure by Letters Patent is:

1. A package including a container having a peripheral wall of fibrous material, the upper portion of said wall being cylindrical, a plastic comestible material normally liquid at body temperature and filling said container to the brim, a flanged cap closing the mouth of said container and including a flat disk portion of greater diameter than said peripheral wall and having complete peripheral contact with the upper edge of said peripheral wall and also having contact with the entire top surface of said comestible material, and a flange portion of materially larger diameter than said peripheral wall and presenting an inwardly directed bead spaced below said disk and also spaced above the lower edge of said flange whereby upon applying said cap the lower edge of the flange will loosely fit over the upper end of said peripheral wall, and upon forcing the cap downwardly said bead will tightly and frictionally engage with the outer surface of said peripheral wall to retain said cap.

2. A container having a peripheral wall of fibrous material, the upper portion of said wall being cylindrical, and a flanged cap closing the mouth of said container and including a flat disk portion of greater diameter than said peripheral wall and having complete peripheral contact with the upper edge of said peripheral wall, and a flange portion of materially larger diameter than said peripheral wall and presenting an inwardly directed bead spaced below said disk and also spaced above the lower edge of said flange whereby upon applying said cap the lower edge of the flange will loosely fit over the upper end of said peripheral wall, and upon forcing the cap downwardly said bead will tightly and frictionally engage with the outer surface of said peripheral wall to retain said cap.
